Patented Nov. 9, 1915.

UNITED STATES PATENT OFFICE.

FREDERIC C. CORNELL, OF NEW YORK, N. Y.

CATAMENIAL APPLIANCE.

1,159,362.

Specification of Letters Patent.

Patented Nov. 9, 1915.

Application filed July 19, 1912. Serial No. 710,498.

To all whom it may concern:

Be it known that I, FREDERIC C. CORNELL, a citizen of the United States, residing at the borough of Manhattan, city, county, and State of New York, have invented certain new and useful Improvements in Catamenial Appliances, of which the following is a specification.

This invention relates to catamenial bandages, and aims to provide certain improvements therein.

The present invention provides a substitute for the usual napkins worn by women, the object being to provide an appliance of this type which is adapted to receive a suitable absorbent pad which may be securely attached to and detached from the bandage and discarded when used.

A further object is to provide an appliance of this character in which there is no danger of soiling the clothing, the construction being such as to prevent any leakage around the pad or through the pad holder.

A further object of the invention is to provide an appliance in which the usual napkin may be employed and securely retained in place, in the absence of the special absorbent pad which is provided for use in connection with the invention.

In the preferred construction of my invention, I employ a waist band or strap which is adapted to be adjustably secured around the person, and upon this band are secured a number of tapes of suitable construction, at least two of which are preferably elastic or provided with elastic portions, and are adapted for adjustment to suit the proportions of the individual using the same. The holder preferably comprises a more or less elongated or rectangular member of fabric adapted to receive the strains of use and to support the absorbent pad, an impervious lining of oil silk, rubberized cloth, or other suitable material being arranged on the upper surface of the holder. At each end of the holder is preferably provided a flap bearing a fastener or fasteners which are adapted to coact with complementary fasteners provided upon the absorbent pad. The holder is so constructed that if a supply of absorbent pads are not readily obtainable, an ordinary napkin may be folded and secured to the flaps by safety pins or the like.

An important feature of the invention is the construction of the holder, which is so formed that it is capable of conforming to

the contour of the body between the limbs of the user, so that it does not chafe or irritate the skin, while it engages the body so closely as to prevent any leakage around the holder, and the straps are so arranged that the ends of the holder are spread laterally in a manner to be described.

In the accompanying drawings, wherein I have illustrated the preferred form of my invention, Figure 1 is a perspective view of the device as a whole; Fig. 2 is a perspective view of the holder extended, and illustrating the method of use of the latter in connection with an ordinary napkin; Fig. 3 is a view on a smaller scale of the two sections of which the holder is preferably formed; Fig. 4 is a view illustrating the front of the appliance in use.

Referring to the drawings, let A indicate the holder, which is shown as constructed of two sections a b, shown in plan in Fig. 3. The sections a b are constructed of canvas or other suitable cloth adapted to bear the necessary strains of use, and are somewhat curved in outline so that when the inner edges thereof are united the outer edges are of somewhat greater extension. This construction is important as it enables the holder to conform to the contour of the body between the limbs of the user, as best illustrated at x in Fig. 4. It will be seen from this figure that the sides of the holder extend more or less vertically along the limbs of the user, while the central part occupies a higher position. By thus conforming to the body, the tension upon the various parts of the holder is equalized, so that there is no liability to chafe or irritate the skin, as would be the case if the holder were flat. Furthermore the holder remains so adjusted and is not liable to roll or turn inwardly or outwardly and thus reduce its effective width to the point where leakage is possible. Moreover by thus conforming closely to the contour of the body, all bulkiness or bulging is avoided. On the inner side of the holder A is provided an impervious lining c, which is preferably of oil silk or other waterproof material. At each end of the holder is formed a flap d d, each of which is shown as stitched along its outer edge to the end of the holder. The flaps d d are provided with a form of fastening means e, shown as the socket of a fastener of the glove type.

The holder A is primarily adapted to re-

ceive an absorbent pad B, which is preferably formed of cheese cloth or other loose cloth lined with absorbent cotton or other absorbent material, which is indicated by the reference letter f. Each end of the absorbent pad B is provided with a fastening device g, which as shown is adapted to enter the socket e of the fasteners of the flaps d. By this means the absorbent pad is very quickly adjusted in place and detached after use, without any danger of soiling the fingers or clothing. According to the present invention the pads B are adapted to be separately sold and to be utilized in connection with the holder in accordance with requirements.

When a supply of absorbent pads is not obtainable for any reason, the device is adapted to be used with an ordinary napkin, which is illustrated in Fig. 2 by the letter C. In use in this manner the flaps d are folded over the ends of the napkin, and any convenient fastening means, such as the safety pins h, are utilized to hold the napkin in place.

The device is admirably adapted to support either the absorbent pad or napkin in an extended position in use, so that the pad or napkin is not wrinkled but is held in a smooth and comfortable position on the body of the wearer.

I provide a supporting means for the device, which means are so attached to the device as to hold it securely and smoothly against the limbs and body of the wearer. These means comprise straps or the like which are attached to the device at or near the outer edges of the latter, so that in use these outer edges are caused to hug the limbs closely, thus preventing any leakage on to the clothing. In the construction shown the straps are lettered j k l m, two being arranged at the front of the device and two at the rear of the device. I preferably introduce elastic tapes n n in the front supporting straps so that a certain amount of elasticity is secured, thereby permitting the user to sit or assume different positions without any danger of sagging.

Preferably a waist band D is provided to support the device, the straps j k l m being preferably looped to permit the waist band to pass through. The straps are fixedly secured to the waist band in the position shown in Fig. 4, so that a further tendency is exerted to hold the edges in contact with the limbs. The straps are fixed to the waist band at such points as best suit the individual figure, and as the straps are looped about the waist band the device is held together during the process of fitting the figure.

An important feature of the invention is the provision of a bandage which is longer at its sides than at its middle in connection with straps which are attached at or near the

sides, since by this means a bandage is provided which hugs the limbs of the wearer so that leakage is prevented. Furthermore these advantages are obtained without the use of side straps extending around the limbs, since I have found that the top straps with the peculiar shape of bandage produce a snugly fitting device without the aid of other supports. There is no danger of doubling up the device so that leakage is possible around its side edges.

By means of the buckles and analogous fasteners in front of the device, the bandage may be temporarily released or removed for the purpose of changing the pads or for other purposes. In order to change the pads it is only necessary to unbuckle the straps j k and grasp one corner of the pad and then pull it from its fasteners, whereupon a fresh pad may be easily adjusted in place.

In the use of my invention it is adjusted about the person of the wearer, and the straps j k tightened until the bandage assumes a comfortable position. When the device is properly adjusted, there is no danger of slipping of the bandage or leakage from the absorbent pad B or C. Furthermore the device as constructed very closely fits the form of the wearer, so that there is no appreciable bulging effect, and its use even with the tightest and thinnest garments is not apparent to the observer. The invention is admirably adapted for summer wear when the clothing of the wearer is light and easily soiled, and also for use in theatrical or other purposes where the clothing of the wearer conforms very closely to the person.

While I have described in detail one form of my invention, I do not wish to be limited thereto, as various changes may be made therein without departing from the spirit of the invention.

I claim as my invention:

1. A catamenial bandage comprising suspensory means, an absorbent pad, and a holder, said holder being formed of two strips of material joined together at their inside edges and extending from end to end of the holder, said inner edges being cut on concave curves extending from end to end of the holder, and said suspensory means being attached to said holder at both ends thereof at the outside edges thereof, said suspensory means being adapted to pull on the outer edges in such manner as to hold the sides and outer edges of the holder closely against the limbs of the user when in use without the aid of other extending means and in such manner that the pressure of said outer edges of the holder upon the limbs of the user may be adjusted by drawing up said suspensory means.

2. A catamenial bandage comprising suspensory means, an absorbent pad, and a

- holder, said holder being formed of two strips of material joined together at their inside edges and extending from end to end of the holder, said inner edges being cut on 5 concave curves extending from end to end of the holder, and said suspensory means comprising a waist band and straps adjustable circumferentially of said waist band, said straps being attached to said holder at 10 both ends thereof at the outside edges thereof, said straps being adapted to pull on the outer edges of said holder in such manner as to hold the sides and outer edges of the holder closely against the limbs of the user 15 when in use without the aid of other extending means, and in such manner that the pressure of said outer edges of the holder upon the limbs of the user may be adjusted by drawing up and circumferentially spacing 20 apart said straps.
3. A catamenial bandage comprising suspensory means, an absorbent pad, and a holder, said holder being formed of two strips of material joined together at their 25 inside edges and extending from end to end of the holder, said inner edges being cut on concave curves extending from end to end of the holder, and said suspensory means being attached to said holder at both ends 30 thereof at the outside edges thereof, said suspensory means being adapted to pull on the outer edges in such manner as to hold the sides and outer edges of the holder closely against the limbs of the user when 35 in use without the aid of other extending means and in such manner that the pressure of said outer edges of the holder upon the
- limbs of the user may be adjusted by drawing up said suspensory means, and said holder having a flap at each end, said flaps 40 having fasteners by which they are adapted to be fastened to such a pad, and being also adapted to be folded over an ordinary napkin and pinned thereto.
4. A catamenial bandage comprising suspensory means, an absorbent pad, and a holder, said holder being formed of two strips of material joined together at their inside edges and extending from end to end of the holder, said inner edges being cut on 45 concave curves extending from end to end of the holder, and said suspensory means being attached to said holder at both ends thereof at the outside edges thereof, said suspensory means being adapted to pull on the outer edges in such manner as to hold the sides and outer edges of the holder closely against the limbs of the user when 50 in use without the aid of other extending means and in such manner that the pressure of said outer edges of the holder upon the limbs of the user may be adjusted by drawing up said suspensory means, and means for holding the suspensory means more widely separated at their upper ends 55 than at their lower ends.

In witness whereof, I have hereunto signed my name in the presence of two subscribing witnesses.

FREDERIC C. CORNELL.
